(57) **CLAIM**

The ornamental design for an eyeglass holder, as shown and described.

DESCRIPTION

FIG. 1 is a side view of an eyeglass holder showing my new design;

FIG. 2 illustrates a longitudinal-sectional view of FIG. 1 shown in mirror-image thereof;

FIG. 3 illustrates a top plan view thereof;

FIG. 4 illustrates a top perspective view thereof;

FIG. 5 illustrates a right-side view thereof;

FIG. 6 illustrates a left-side view thereof;

FIG. 7 illustrates a bottom perspective view thereof;

FIG. 8 illustrates a top perspective view thereof as shown in FIG. 4 with the detachable button having been removed; and,

FIG. 9 illustrates a perspective view of the detachable button.
